United States Patent Office

Des. 195,815
Patented Aug. 6, 1963

195,815

SOAP HOLDER

John Louis Jaffe, Vincent Rodin, and Mort L. Rothenberg, all of 255 5th Ave., New York, N.Y.

Filed Feb. 16, 1962, Ser. No. 68,862

Term of patent 3½ years

(Cl. D4—3)

FIG. 1.

FIG. 2.

FIG. 3.

FIG. 1 is a front perspective view of a soap holder, showing our new design;

FIG. 2 is a front elevational view thereof;

FIG. 3 is a side elevational view thereof.

The bottom of the cylindrical portion beneath the top at the front of the soap holder is closed.

We claim:

The ornamental design for a soap holder, substantially as shown and described.
